[57] **CLAIM**

The ornamental design for an elevated creeper for automotive mechanics, as shown and described.

DESCRIPTION

FIG. 1 is a front left perspective view of an elevated creeper for automotive mechanics;

FIG. 2 is an elevational view of one side thereof, the opposite side being a mirror image;

FIG. 3 is a elevational view similar to FIG. 2 but showing the creeper board support pipes clamped in elevated position;

FIG. 4 is a front elevational view thereof;

FIG. 5 is a rear elevational view thereof;

FIG. 6 is a top plan view thereof; and,

FIG. 7 is a bottom plan view thereof.

FIG - 4FIG - 5FIG - 6FIG - 7
